GRANT I. RAWSON, OF DETROIT, MICHIGAN, ASSIGNOR TO CALORIZING CORPORATION OF AMERICA, OF DETROIT, MICHIGAN

BOILER CLEANER

Application filed November 2, 1921, Serial No. 512,219. Renewed July 10, 1931.

My invention relates to new and useful improvements in boiler cleaners and has for its object the provision of an automatic boiler cleaner, arranged to operate automatically at pre-determined intervals and so constructed as to prevent the delivery of cleaning fluid at improper intervals against any particular part of the boiler.

Another object of the invention is to provide an automatic means for expelling moisture from the main header of the blower system previous to the blowing operation and to close in said header a drain valve normally held open.

Another object of the invention is the provision in a boiler cleaner, designed to operate automatically, of means for insuring prompt and efficient closing of a valve positioned in the main header so as to prevent delivery of cleaning fluid to the boiler in case the operating means for the blower system should become disarranged.

Another object of the invention is the provision in the main header of a slowly opening valve so as to cause a slow and gradual delivery of cleaning fluid to the main header, so as to cause a gradual warming up of the same and expulsion of moisture therefrom.

Other objects will appear hereinafter.

The invention consists in the combinations and arrangements of parts hereinafter described and claimed.

The invention will be best understood by reference to the accompanying drawings which form a part of this specification and in which,

Fig. 1 is a side elevational view of the invention.

Fig. 2 is a top plan view of the invention.

Fig. 3 is a sectional view taken on substantially line 3—3 of Fig. 2.

Fig. 4 is a sectional view taken on substantially line 4—4 of Fig. 2.

Fig. 5 is a sectional view taken on substantially line 5—5 of Fig. 2.

Fig. 6 is a sectional view illustrating the solenoid and trip used in the invention.

Fig. 7 is a sectional view taken on substantially line 7—7 of Fig. 6.

Fig. 8 is a view similar to Fig. 6, showing the trip in inoperative position.

Fig. 9 is a perspective view of the trip used in the invention.

Fig. 10 is a central vertical sectional view of the drum used in the invention.

Fig. 11 is a vertical cross-sectional view of the drum used in the invention.

Fig. 12 is a diagrammatical view of the invention showing its layout.

Figure 13 is a diagrammatic view showing the drain valve in its relation with the supply pipe and the blower units.

Figure 14 is a semi-diagrammatic elevational view of the motor and switch mechanism for operating each of the respective blowers.

By my invention I have designed to overcome some difficulties which have presented themselves in automatic systems of soot blowers. With automatic systems of soot blowers, as at present in use, it is customary to use a cam actuated valve for controlling the delivery of steam, or other cleaning fluid, to the blower unit which projects into the setting of the boiler. This valve is positioned in close proximity to the head and is opened and closed by a cam which rotates synchronously with the blower unit. The rotation of the unit is effected by a motor. While the cleansing fluid is being projected from the blower unit, it is necessary that the unit be in rotation, so that there may be no prolonged blowing from the unit against any part of the boiler. In case the motor should become disarranged while the valve is opened and while the fluid is being projected from the unit, the tubes of the boiler might be very quickly seriously damaged were there not some way arranged to automatically shut off the supply of fluid to the unit. This difficulty I have overcome by providing an automatic means for closing a valve in the main header when any disarrangement takes place with the rotating means.

Another difficulty which it is desired to overcome in soot blower systems is the projection of liquid into the blower unit and onto the tubes, thereby causing the soot and ashes clinging thereon to bake on the tubes.

To overcome this difficulty I have provided means for slowly opening the valve in the main header which permits a small amount of steam to pass through the header, thereby warming the same up and expelling the moisture from the open end of the header, which is controlled by a drain valve normally held open. In this invention the drain valve is arranged to be closed by means which does not effect a closing until after sufficient cleansing fluid has passed through the main header to expel the moisture therefrom and warm the header up so as to prevent condensation therein.

The invention comprises a base 15, projecting upwardly, from which is a brace 16 upon which a motor 17 is mounted, the shaft 18 of said motor having a worm 19 fixedly fastened thereto and meshing with a gear 20 which is mounted upon a shaft journaled in suitable bearings mounted on said base. Said shaft carries fixedly mounted thereon, a gear 21 which meshes with a gear 22, said gear 22 being mounted upon a shaft 23 journaled in suitable bearings supported by brackets 24 and 25, projecting upwardly from said base. Said gear 22 has fixedly secured to one of its faces, a cam 26 which engages a roller 28 loosely mounted on the free end of a lever 27. The opposite end of lever 27 is pivotally connected to a yoke 41 carried on the upper end of a stem 42' for controlling the elevation of the fulcrum point of lever 27 as will later be apparent. Said lever 27 is pivotally secured, intermediate its ends, to a stud 29 which passes through an eye formed in a lever 31, a spiral spring being positioned upon said stud intermediate said lever 27 and said lever 31. Lever 31 is fastened pivotally at its opposite end to an upright 32 projected from the base 15. Pivotally attached to the lever 31, intermediate its ends, is a valve stem 33 designed to operate the valve 34 which is interpositioned in a pipe 35 which communicates with the main header 39. A pipe 36 communicates with the valve 34 and leads to a drain valve 34^a interposed in the header 39. This drain valve is normally held open by a spring 34^b in the usual manner, and the pipe 36 communicates with cylinder 34^c associated with said valve so that steam passing through member 36 will act on piston 34^d mounted on valve stem 34^e and cause the drain valve to close against the tension of the spring which normally holds it open. Pivotally secured to the lever 27, adjacent one end thereof, is a valve stem 37 which projects into the valve 38 positioned in the main header 39 and designed to control the passage of fluid through said header. A spiral spring 40 is secured to said lever 27 and to a collar 41' secured to the header 39. Pivotally mounted at one end upon the bracket 25 is a lever 42, the other end of which is secured pivotally to a stem 42'. Fixedly mounted upon the stem 42' is

a collar 43 on which is pivotally mounted at one end, a trip or paul 44, said stem being slideably positioned in a block 45 which is secured to a base 47, said base 47 being mounted upon the header 39 by means of a U-bolt 46. Pivoted to the lower end of the paul or trip 44, is the core 48 of the solenoid 50, said core projecting through said solenoid and having a spiral spring 49 positioned thereon, normally retaining said paul or trip in inoperative position as shown in Fig. 8. When in inoperative position the shoulder 44' is moved away from the edge of the member 45 as shown in Figure 8, thereby lowering the collar 43 and the fulcrum point of lever 27 permitting spring 40 to close valve 38 and spring 30 to close valve 34.

The construction is such that upon turning of the wheel 22 through driving the motor 17, the cam engages the roller 28 and thereby lifts the free end of the lever 27 so as to cause the valve 38 to open gradually. It will be noted that the valve 38 opens gradually while at the same time the valve 34 begins to open more slowly, so that a considerable amount of steam is allowed to pass through the header 39 by the valve 38 before the valve 34 becomes fully opened so as to allow a sufficient amount of steam to pass through the pipe 36 to close the drain valve. When the device is in operation, the paul 44 is in the position shown in Figure 6, whereby the fulcrum 41 of the lever 27 is elevated relative to the position shown in Figure 8. It is on the fulcrum 41 that the lever 27 operates in opening the valves 38 and 34. The springs 30 and 40 serve to close the valves when the roller 28 rides off of the periphery of the cam 26.

As shown in Fig. 12, it is designed to operate the device from a clock system although it is not necessary inasmuch as the device may be hand-operated by closing the switch manually instead of by the clock. A switch 50' is provided into which lead the positive and negative wires respectively 52 and 51. A wire 53 leads from the switch and communicates with contact member 84, the purpose of which will be explained later. This wire 53 also is connected by means of a wire 55 to the solenoid 50. Leading from the other end of the switch 50' is a wire 56 which connects to a contact member 57, said member 57 being so positioned as to brush against the metallic band 60 positioned upon the drum 60' which is mounted on the shaft 23.

It is to be noted that the wire 56 is connected by means of a wire 59 to the clock 59'. The wire 63 leads to the motor 17 and is connected to the clock 59'. This wire 63 is also connected by a wire 62 to the solenoid 50. This wire 62 also connects with contact member 61', contact member 61' being designed to serve as a brush in contact with a metallic continuous band 61 positioned upon the drum 60'. The contact member 57 is mount-

ed upon an insulating platform 58 which is positioned upon pedestals 58' which are secured to the base 15. Contact member 70' is likewise mounted on platform 58 and is designed through the wire 76 to close the circuit leading to the motor 70 used to drive a particular blower unit. Similarly contact member 71' is mounted on the insulating platform 58 and is designed through the wire 77 to close the circuit leading to the motor 71. Likewise, the other contact members 72', 73', 74', and 75' are mounted on the insulating platform 58 and are designed to close the circuits of the motors 72, 73, 74 and 75 through the wires 78, 79, 80 and 81 respectively.

It is to be noted that the wire 63 is connected through switches 64, 65, 66, 67, 68 and 69 with the motors used for driving the units and wire 70" leading from said switch 64 to the motor 70, a wire 71" leading from the switch 65 to the motor 71, a wire 72" leading from the switch 66 to the motor 72, a wire 73" leading from the switch 67 to the motor 73, a wire 74" leading from the switch to the motor 74 and a wire 75" leading from the switch 69 to the motor.

It is to be noted that the contact member 83 which serves as a brush upon the continuous metallic band 82 positioned upon the drum 60' is connected by the wire 83' with each of the motors used to drive the unit. The contact member 84 which also serves as a brush on the metallic member 82 is connected by the wire 53 to the switch 50' and by a wire 55 to the solenoid 50, thereby closing the circuit.

It is to be noted that member 60 is interrupted but is short-circuited to the member 61 by the conductor 87 extending through the center of the drum 60' and the branch conductors 87' and 87" extending from the conductor 87 to the members 60 and 61 respectively. A step 85 is provided in the path of the band 60 so as to afford a quick make and break. Each of the members 70', 71', 72', 73' and 74' in the course of the rotation of the drum 60' come into contact preferably successively with contact members 86 which are connected as shown in the diagram. Each contact member 70', 71', 72', 73' and 74' engages successively a contact member 86 similar to that shown for contact member 73' in Figure 4. Fig. 10 shows the manner of connecting contact members 86 through the drum with the contact strips 60 and 61 and thus with the lead 56 from switch 50'. From this view it will be noted that the contact members 86 are respectively connected by the conductors 88 to the central conductor 87 and that this central conductor extends substantially the entire length of the drum. As each contact member successively engages the small strip 86, the circuit through the motor driving its respective unit is closed

and the motor is thereby automatically set into operation to rotate the unit.

When the clock makes the contact, the motor 17 is set into operation, causing the drum to rotate from the position shown in Fig. 2, so that the contact member 57 engages the metallic strip which is short-circuited to the continuous metallic strip 61, thereby affording a closed circuit through the motor 17 after the clock breaks its connection. The motor 17, therefore, will continue to rotate until the contact member 57 reaches the interrupted portion of the band 60.

It is to be noted that the solenoid is also magnetized at the same time the motor 17 begins to rotate, so that the trip 44 is moved into close engagement against the side of the member 45, thereby locking the fulcrum 41 for the end of the lever 27 which as shown in Figure 6 is elevated relative to the position shown in Figure 8. Whenever the circuit is broken while the roller 28 is in engagement with the circular portion of the periphery of the cam 26, the solenoid will be de-energized and the spring 49 will cause the member 44 to disengage from member 45 thereby lowering the fulcrum point of lever 27 from the position shown in Figure 6 to that shown in Figure 8, thus allowing the valve 38 to be closed in response to the tension of the spring 40.

The switches 64, 65, 66, 67, 68 and 69 are placed in such positions with respect to their respective cams which open the respective valves which permit the delivery of fluid to the respective blower units, as to retain said switches in closed positions as long as the respective valves are open. The structure for accomplishing this is clearly illustrated in Figure 14.

By reference to this figure it will be noted that the motor 70 is adapted to drive the blower element 101 through a worm 102 and a gear 103 mounted on the blower element. A cam 104 carried by the gear 103 functions to engage the valve stem 105 upon rotation of the blower element and to thereby depress and open the valve 106 in the supply pipe 107. For effecting a closing of the switch 64 upon the opening of the valve 106 there is provided an arm 108 rigidly carried by the valve stem 105 and this arm carries at its outer free end, a contact 109 adapted to bridge the contacts 110 and 111 of the switch 64. It will thus be seen that operation of the blower element by the motor 70 will cause the cam 104 to engage valve stem 105 to open the valve 106 and to close the switch 64. Obviously when the flattened portion of the cam approaches the valve stem, the spring 112 will tend to close the valve 106 and open the switch 64.

Considering the operation of, for example, the motor 70 in its relation to the general arrangement and by reference particularly to Figures 12 and 14, it will be noted that when

contact 70' engages its respective contact 86, current will momentarily be supplied to the motor 70 through the conductor 53, contact 84, band 82, contact 83, and wire 83' on one side and conductor 56, contact 57, member 60, conductors 87 and 88, contact 86, member 70' and conductor 76 on the other hand. This will start the rotation of the motor 70 whereupon cam 104 will open valve 106 and close switch 64. Obviously upon the continued rotation of the drum 60' the contact of member 70' with contact 86 will be broken so that the motor 70 will no longer obtain current through the conductors aforesaid.

16 However when this condition is reached, the motor 70 will then be supplied current through the conductor 53, contact 84, member 82, contact 83 and conductor 83' on one hand and conductor 63, switch 64, and conductor 70'' on the other hand. It will thus be seen that while the drum 60' initially closes the circuit to the motor 70 that the circuit to this motor is maintained closed by the switch 64.

20 25 In the further operation of the structure and by reference particularly to Figure 1, it will be noted that when the motor 17 is operating the solenoid 50 will be energized and the fulcrum 41 of the lever 27 will be in the position shown in Figure 6. This will raise the one end of the lever 27 and the other end of the lever 27 will be raised by the riding of the roller 28 on the circular portion of the cam 26. This will cause an opening of the 30 35 valves 34 and 38 in the manner brought out before and it will be noted that neither of these valves will be opened until both ends of the lever 27 are raised.

Obviously upon rotation of the cam 26 to a point where the cut out portion engages the roller 28 the arm 27 will be lowered to such an extent as to permit closing of the valves 34 and 38 by the spring 30 and 40 respectively.

40 45 The solenoid 50 serves as a means to prevent damage of the boiler tubes should any part of the system become disarranged. Since it is obvious that both ends of the lever 27 must be raised to actuate the valves 34 and 38, it is obvious that if the end of the lever 27 which is fulcrumed as at 41, is lowered, then the valves will be closed. In the operation therefor, upon disarrangement of any portion of the electrical system, such for example as the failing of motor 70, the main fuses in the entire system will be blown whereby the solenoid 50 will be de-energized, the fulcrumed end of the lever 27 will be lowered and the valves 34 and 38 will be closed. Referring to Figure 13 it will be noted that when the valve 38 is closed the drain valve 34' will be open whereby the blower units and piping leading thereto will be drained. On opening the valve 38 for a small amount the system is warmed up, the condensate es-

caping by way of valve 34 until the pressure builds up sufficiently to close valve 34'. By this time the valve 38 will be fully operated.

While I have illustrated and described the preferred form of construction, I do not desire to limit myself to the precise details of construction set forth but desire to avail myself of such modifications and changes as come within the scope of the appended claims. Further, while the invention has been described as being embodied in a boiler cleaner for cleaning parts of a boiler, it will be apparent that the invention will find equal utility in devices for cleaning similar types of apparatus, and it is to be therefore understood that the term "boiler" wherever used in the specification or claims is to be construed as meaning a heat transfer apparatus or fluid heater of any character, while the term "boiler cleaner" is to be construed as meaning a cleaner for any such apparatus.

It will be obvious that, if desired, the above described control system may be used to control the operation of a plurality of cleaning systems for a plurality of boilers. Thus, any one of the contacts 86 on the drum 60' might be electrically connected to a motor similar to the motor 17 but associated with the cleaning system of a second boiler, whereby this contact would function in a manner similar to the clock 59' to momentarily start the actuation of the second motor which would drive a second drum in the same manner as the motor 17 drives drum 60'.

Having thus described my invention what I claim is new and desire to secure by Letters Patent, is:

1. In a soot blowing system comprising a main header and a plurality of blower units communicating therewith, means for rotating each of said units; means for actuating the said rotating means; control means in said header; a normally open drain valve in said header; means for closing said drain valve; and means for operating said header control means synchronously with the actuation of said closing means, the operating of said header control means being incipiently more rapid than the actuation of said closing means.

2. In a soot blowing system, a plurality of blower units, motors for separately rotatively driving the units, a movable contact carrying circuit closer for said motors, a main valve controlling the fluid supply to said units, a normally open drain valve control means for said main valve and drain valve, and a common drive means for said circuit closer and for said main and drain valve controlling means.

3. In a soot blower system, a blower unit, a main cleaning fluid header, a drain valve for said header, a control valve for said header, an individual control valve for con-

trolling the supply of cleaning fluid from said header to said blower unit, an auxiliary valve for controlling the actuation of said drain valve, automatic means including a rotatable drum for controlling said individual valve, means including a cam for automatically controlling said header controlling valve and said auxiliary valve in timed relation to the control means for the said individual valve and a common shaft carrying said drum and cam.

4. In a soot blower system, a plurality of blower units, a main control valve for all of said units, individual control valves for the several units, automatic control means for each of said individual valves, means for automatically controlling said main valve in timed relation to the control means for the individual valves, a drain valve for draining the blower units during periods of non-use of the blower units, and means including an auxiliary valve controlled by the said main valve control means for closing the drain valve after a predetermined time following the opening of the said main valve.

5. In a soot blower system, a blower unit, a main cleaning fluid header, a control valve for said header, an individual control valve for controlling the supply of cleaning fluid from said header to said blower unit, automatic control means for said individual valve, and means for automatically controlling said header controlling valve in timed relation to the control means for the said individual valve, a drain valve for draining the blower unit during periods of non-use of the blower unit, and means including an auxiliary valve controlled by the said main valve control means for closing the drain valve after a predetermined time following the opening of the said main valve.

6. In a soot blower system, a blower unit, a main cleaning fluid header, a control valve in said header, an individual control valve for controlling the supply of cleaning fluid from said header to said blower unit, automatic control means for said individual valve, means for automatically controlling said header controlling valve in timed relation to the control means for said individual valve, a drain valve for draining the blower unit during periods of non-use of the blower unit, and means controlled by the said main valve controlled means for closing the drain valve after a predetermined time following the opening of the said main valve, said last mentioned means including a lever for actuating said header controlling valve and said drain valve and separate members for elevating opposite ends of said lever.

7. In a soot cleaning system comprising a main header having a plurality of blower units communicating therewith, means for rotating each of said units, means for actuat-

ing said rotating means separately, means for moving said actuating means, a control valve mounted in said header, a drain valve in said header and means controlling the operation of said drain valve and mechanically connecting said control valve and actuating means for opening said control valve and for effecting an actuation of said drain valve upon the movement of said actuating means.

8. In a soot blower system, a main header, a plurality of blower units communicating with said main header, a normally open drain valve for said header, a main valve for controlling the flow of cleaning fluid to said header, a by-pass around said main valve for conducting cleaning fluid to said drain valve to close the same, and an auxiliary valve controlling the flow of fluid through said by-pass.

9. In a soot blower system, a main header, a plurality of blower units communicating with said main header, a normally open drain valve for said header, a main valve for controlling the flow of cleaning fluid to said header, an auxiliary valve for controlling the flow of cleaning fluid to said drain valve to close the same, and a common means for actuating said main valve and said auxiliary valve.

10. In a soot blower system, a main header, a plurality of blower units communicating with said main header, a normally open drain valve for said header, a main valve for controlling the flow of cleaning fluid to said header, an auxiliary valve for controlling the flow of cleaning fluid to said drain valve to close the same, and a common means for actuating said main valve and said auxiliary valve, said last mentioned means including a fulcrumed lever connected intermediate its ends to the said main valve and the auxiliary valve.

11. In a soot blower system, a main header, a plurality of blower units communicating with said main header, a drain valve for said header, a main valve for controlling the flow of cleaning fluid to said header, an auxiliary valve for controlling the flow of cleaning fluid to said drain valve to close the same, and a lever for actuating said main valve and said auxiliary valve, said lever being positioned to actuate one of said valves more rapidly than the other.

12. In a soot blower system, a main header, a plurality of blower units communicating with said header, an electric motor for each of said blower units, a main valve for controlling the flow of cleaning fluid to said main header, a normally open drain valve for said header, an auxiliary valve for controlling the flow of cleaning fluid to said drain valve to close the same, a lever for actuating said main valve and said auxiliary valve, and means for rendering said lever operative in synchro-

nism with the supply of electric current to said motors associated with said units.

13. In a soot blower system, a main header, a plurality of blower units communicating with said header, an electric motor for each of said blower units, a main valve for controlling the flow of cleaning fluid to said main header, a normally open drain valve for said header, an auxiliary valve for controlling the flow of cleaning fluid to said drain valve to close the same, a lever for actuating said main valve and said auxiliary valve, means for rendering said lever operative in synchronism with the supply of electric current to said motors associated with said units, and means for rendering said lever inoperative upon failure of the supply of current to the said individual motors.

14. In a boiler cleaner, a movable blower element, means for moving said blower element, a valve for controlling the flow of cleaning fluid to said blower element, and plural means operating to hold said valve open during movement of said blower element by said blower element moving means, one of said plural means operating to close said valve upon failure of said blower element moving means to move said blower element irrespective of the position of the other of said holding means.

15. In a boiler cleaner, a movable blower element, electrically actuated means for moving said blower element, a valve for controlling the flow of cleaning fluid to the blower element, and plural means for opening said valve upon the closing of a circuit through said electrically actuated blower element moving means and for holding said valve open during movement of said blower element, one of said plural means operating to close said valve upon the shorting of the electric circuit through the blower element actuating means irrespective of the position of the other of said holding means.

16. In a boiler cleaning system, a plurality of blower elements, electrically actuated means for controlling the actuation of said blower elements, a main valve for controlling the flow of cleaning fluid to all of said blower elements, means operable to open said main valve actuated by the energization of said electrically actuated means, and means operable to close said main valve upon the interruption of the flow of current to the system.

17. In a boiler cleaner, a rotatable blower element, means for rotating said blower element, a valve for controlling the flow of cleaning fluid to said blower element, a lever for actuating said valve, and means for rendering said lever inoperative to provide for closing of said valve upon failure of said blower element rotating means to rotate said blower element.

18. In a boiler cleaner, a rotatable blower element, means including an electric motor

for rotating said blower element, a valve for controlling the flow of cleaning fluid to said blower element, means including a lever for actuating said valve, and means electrically connected in the circuit with said electric motor for rendering said lever inoperative to provide for closing of said valve upon shorting of the circuit through the said motor.

19. In a soot cleaning system, a plurality of blower units, a main header for supplying cleaning fluid to said blower units, a valve in said main header, an electric motor associated with each unit for rotating the same, a rotatable drum, a plurality of contacts on said drum arranged to successively close the circuits through said electric motors upon rotation of said drum, and means mechanically connecting said rotatable drum to said valve to actuate the latter upon rotation of the drum.

20. In a boiler cleaner, a blower element, a header for supplying cleaning fluid to said blower element, a normally open drain valve for said header, a main valve for controlling the flow of cleaning fluid through said header, and means for closing said drain valve upon the expiration of a predetermined time interval after the opening of said main valve to provide for draining of said header prior to the closing of said drain valve.

21. In a boiler cleaner system, a plurality of movable blower elements, means associated with each element for moving the same, power actuated control means for said element moving means, a cleaning fluid supply header, a control valve in said header, actuating means for said control valve actuated by the power supplied to said power actuated control means, and means to automatically close said supply valve upon the interruption of power to said power actuated control means.

22. In a boiler cleaner system, a plurality of movable blower elements, means associated with each element for moving the same, power actuated control means for said element moving means, a cleaning fluid supply header, a control valve in said header, a drain valve for said header, actuating means for said control valve and drain valve actuated by the power supplied to said power actuated control means, and means to automatically close said supply valve upon the interruption of power to said power actuated control means.

In testimony whereof, I have hereunto signed the foregoing specification, at Detroit, County of Wayne and State of Michigan.

GRANT I. RAWSON.
